(No Model.)

O. S. BETTS.

SPOOL CASE.

No. 388,813.

Patented Sept. 4, 1888.

UNITED STATES PATENT OFFICE.

ORRIN S. BETTS, OF CHICAGO, ILLINOIS.

SPOOL-CASE.

SPECIFICATION forming part of Letters Patent No. 388,813, dated September 4, 1888.

Application filed April 23, 1888. Serial No. 271,589. (No model.)

To all whom it may concern:

- Be it known that I, ORRIN S. BETTS, of Chicago, in the county of Cook and State of Illinois, have invented certain new and useful 5 Improvements in Spool-Cases, of which the following is a full, clear, and exact description, reference being had to the accompanying drawings, forming a part of this specification, in which—
- 10 Figure 1 is a plan view of a spool-case embodying my improvements. Fig. 2 is a sectional view of the same upon the line $x-x$, Fig. 1, viewed in the direction of the arrow there shown. Fig. 3 is a sectional view in detail, 15 taken upon the line $y-y$, Fig. 2, viewed in the direction of the arrow there shown. Fig. 4 is a sectional view in detail of a portion of the case, showing the outer end of one of the spool-holding tubes. Fig. 5 is an enlarged central 20 vertical sectional view in detail of a portion of one of the spool-holding tubes taken upon the line $z-z$, Fig. 3, showing the manner of attaching the cross-slats. Fig. 6 is a vertical sectional view through two of said tubes in the 25 plane of said cross-slats, showing a modified construction; and Fig. 7 is a detail of a portion of the case, partly in section, showing the cutline or delivery end of one of said tubes, in which the construction is somewhat modified.
- 30 Like letters of reference in the different figures represent corresponding parts.
- The object of my invention is to so construct a spool-case as to enable large and small spools of a given color or shade to be kept in independent compartments, so that they may be 35 readily compared with each other, and at the same time to so hold the small or short spools that while they may be easily examined they cannot be misplaced by customers desiring to 40 look at them nor become disarranged in the handling of the case. A further object is to so construct said case that it may be light, strong, and cheaply made, while it will gather and retain but little dust to soil the spools.
- 45 To this end my invention consists in the combination of elements and special features of construction hereinafter more particularly described and claimed.
- 50 Referring to the drawings, A represents a drawer or case of the usual construction, having a glass front, B, to permit the samples to be

seen which indicate the shades in the different drawers, said samples, as c, Fig. 1, being arranged in a trough, C, parallel with the front and separated from the main spool-case by 55 means of a partition, D.

Arranged parallel with each other and lengthwise of the case are a series of tubes, E, the ends of which are rigidly secured in bearings in the partition and the rear end, A', of the drawer, 60 as indicated in dotted lines in Fig. 2. Said tubes are separated from each other a distance of about the length of an ordinary spool, as shown in Fig. 1, and are constructed, preferably, of japanned tin or other sheet metal, and 65 have an inner diameter sufficient to permit the ready insertion of a spool. They are also open at the top throughout their entire length; but the slots, as clearly shown, are narrower in width than the diameter of the tube for a distance from the rear preferably to a point near to 70 the forward end of the tube, from whence they are cut away, as shown at F, to the full diameter thereof for the purpose of inserting and removing the spools. In order to permit the 75 spools to be readily grasped between the thumb and finger, I provide notches D' in the partition D, which notches extend only partially toward the bottom, as more clearly shown in Figs. 4 and 5, thus leaving a ledge to prevent 80 the spools from sliding out of the tubes should the drawer be forwardly inclined; but while I prefer to construct said tubes and notches in the way described, it is obvious that said construction may be modified by cutting the 85 notches D' deep enough to conform to the interior of the tubes, as shown in Fig. 7, in which case said tubes need not be cut away at F, as above described. This construction permits the spools to be directly inserted and 90 withdrawn from the front end of the tube instead of being lifted out, as they otherwise would be.

The making of the slotted tubes as described, with the slots or openings in the top narrower 95 than their respective diameters, as distinguished from the usual grooved trough, is of paramount importance, and constitutes the leading feature of novelty of my invention. The very narrow spools f are constantly liable 100 to fall down and become displaced and disarranged in handling the drawer when mere

grooves are employed, unless the case is full, and then a jar will disarrange them. Moreover, customers in matching shades are very liable to take out the small spools and replace them in the wrong trough, thus requiring much time upon the part of clerks to rearrange and sort them to conform to the shades of the large spools, which should be adjacent thereto; but in my improved tubes, while the shades may be inspected equally well, they cannot be misplaced by being shaken, nor are meddlesome customers likely to confuse them, for the reason that they cannot be lifted from the tube promiscuously, but must be withdrawn from the ends.

Beneath the tubes E, and at right angles to the axes thereof, are secured a series of cross-bars, G, which are arranged parallel with each other and a sufficient distance apart to serve as supports for the usual large spools, g, each row of which is intended, as stated, to correspond in shade with that of the small spools in one of the adjacent tubes, so that after deciding upon a given shade in a large spool its complement in the smaller size may be found at once and without search. Said cross-bars may consist of round rods of metal or wood rigidly secured to said tubes in any well-known way; but I prefer to make them of grooved sheet-metal strips, semicircular in cross-section, as shown, in order to insure lightness and strength as well as a proper bearing surface for the spools, and in order to attach them readily and at a minimum cost I prefer to make them of a depending flange, e, upon the bottom of each tube throughout its length. This may readily be accomplished in the bending or forming of the tube, so as to make the metal of a double thickness. This not only renders the tube stronger, but the fastening is also firmer and more secure. In the flanges e are formed a series of semicircular perforations, e', through which the bars G are inserted, having their convex sides uppermost. In lieu of inserting said bars in the perforations, as described, it is obvious that they may be soldered to the rounded bottom of the tube, as shown at e', Fig. 6; but I regard this as a more costly and inferior construction.

Having thus described my invention, what I claim, and desire to secure by Letters Patent, is—

1. A spool-holding case having a series of spool-holding cylindrical tubes having longitudinal slots or openings in the top thereof of a width slightly less than the diameter of said tubes, in combination with a partition at the receiving end provided with a series of thumb-notches therein conformable to the respective positions of said tubes, substantially as shown and described.

2. In a spool-holding case, a series of spool-holding cylindrical tubes having longitudinal openings in the top thereof of a width slightly less than the diameter of said tubes, and cut-away portions at the receiving ends to the full diameter thereof, whereby a spool may be held within the tube until it reaches said cut-away portion, from whence it may be lifted from the top thereof, substantially as shown and described.

3. In a spool-case, the combination of a series of cylindrical spool-holding tubes having longitudinal slots or openings in the top thereof of a width slightly less than the diameter of said tubes, with a series of cross-bars arranged parallel to each other and at right angles to the axes of said tubes and of such a distance from each other as to support a series of spools thereon, whereby the small spools within the tubes may be compared or contrasted with those upon the cross-bars, substantially as shown and described.

4. The combination, in a spool-holding case, of a series of tubes, E, having perforated depending flanges respectively in the plane of their axes, and a series of cross-bars inserted within said perforations, substantially as shown and described.

In testimony whereof I have signed this specification, in the presence of two subscribing witnesses, this 10th day of April, 1888.

ORRIN S. BETTS.
